AUTOMATIC SAFETY DEVICE FOR INTERNAL
COMBUSTION ENGINES

Leland L. Scott, Kansas City, Mo.

Application April 8, 1937, Serial No. 135,722

5 Claims. (Cl. 123—146.5)

My invention relates to safety devices for internal combustion engines and more particularly to a device for stopping operation of an engine when it exceeds a certain working speed, the principal object of the present invention being to provide a simple and positively operating mechanism to automatically interrupt the ignition circuit of an engine when unsafe speeds are attained.

10 Another important object of the invention is to manually restore functioning of the ignition circuit after the safety device has actuated.

In accomplishing these and other objects of the invention, I have provided improved details of structure, the preferred form of which is illustrated in the accompanying drawing, wherein:

Fig. 1 is a perspective view of a magneto equipped with a safety device constructed in accordance with my invention.

20 Fig. 2 is a longitudinal vertical section through the magneto and safety device.

Fig. 3 is a cross section through the safety device on the line 3—3, Fig. 2.

Fig. 4 is a cross section through the safety device on the line 4—4, Fig. 2.

25 Fig. 5 is a detail fragmentary view of a modified contact arrangement.

Referring more in detail to the drawing:

1 designates a portion of an internal combustion engine equipped with a conventional type magneto 2 for supplying an ignition current by which the fuel in the cylinders is ignited.

The magneto includes a casing 3 for housing the armature 4 and a distributor mechanism 5 which times the points of ignition in the respective cylinders. The armature 4 is mounted on spindles 7 and 8 rotatably mounted in bearings 9 and 10 carried by the casing. The spindle 7 carries a gear 11 meshing with a suitable drive gear on the crank shaft of the engine to rotate the armature at a definite speed relative to that of the engine. The distributing mechanism is operated by a shaft 12 extending in parallel relation to the axis of the armature and has its ends rotatably mounted in anti-friction bearings 13 and 14. The shaft 12 is driven in timed relation with the armature by a gear 15 thereon meshing with a gear 16 on the spindle 8, so that it also is driven at a definite speed relative to the speed of the motor. In order to secure the gear 15, the end of the shaft 12 is ordinarily provided with a shoulder 17 and is threaded as at 18 to receive a suitable nut (not shown) to clamp the gear thereagainst in assuring positive operation of the distributing mechanism. The magneto is

also equipped with a circuit interrupter 19 that is grounded as at 20 to provide an intermittent current to the spark plugs of the engine.

The magneto thus described is of a common type such as used on airplane motors and like engines and specifically forms no part of the present invention other than affording a convenient mounting for my improved safety device, now to be described.

As above mentioned it is the purpose of the 10 safety device to automatically disrupt functioning of the ignition circuit when the engine has attained an excessive R. P. M. and is in danger of "running away" caused by sudden release of the engine from its working load. For example, 15 when an airplane is in flight, the engine is often released from its working load due to loss of the propeller from breakage or other causes, consequently upon relief of its load the speed of the engine increases at a rapid rate to cause excessive vibration. The speed and vibration increase so suddenly that, before the pilot becomes aware of the fact, the engine has shaken itself loose from its support or has caused serious damage to the plane. Even should the pilot 25 notice the sudden racing of the engine, it is physically impossible for him to manually shut off the ignition before damage has resulted.

The present invention forestalls disastrous results by automatically grounding the magneto 30 current, or in case of the ordinary battery ignition, by automatically opening the battery circuit. This is accomplished in the first instance by tripping a switch to closed position and in the latter instance by tripping a switch to open 35 position, as now to be described.

In the illustrated instance the safety mechanism is mounted directly upon the magneto and includes a bell-shaped housing 21 comprising a cylindrical base portion 22 and a cap portion 23 40 which may be formed of insulating material.

The base portion 22 includes a flange portion 24 cooperating with the magneto housing to enclose the gear 15 and is secured in position by fastening devices 25 extending through openings 26 in 45 the flange portion and into threaded openings 27 in the magneto casing, as shown in Fig. 2. The opposite end of the portion 22 terminates in an inwardly extending flange 28 forming a seat 29 for an annular flange 30 of the cap portion 23, 50 which is secured thereto by fastening devices 31.

Mounted on the end of the shaft 12 is a governor carrier member 32 including a cylindrical body 33 provided with an internal cylindrical socket 34 having threads 37 conforming to the 55

threads 18 on the shaft 12 to retain the carrier thereon and to take the place of the nut usually employed to clamp the gear 15 against the shoulder 17. The body of the carrier is slotted 5 at opposite diametrical points, as at 38 and 39, and carries spaced ears 40 and 41 extending radially from opposite side edges of the slots to accommodate governor arms 42 and 43 there-between.

10 The governor arms include bell crank levers having hub portions 44 pivotally mounted on pins 45 having their ends mounted in the ears 40 and 41. The outer arms 46 of the levers normally extend in parallel relation to the axis of the shaft and carry governor weights 48 while the inner arms 49 extend within the socket 34 to engage the head 50 of a trip pin 51 which is slidably mounted therein and has its shank 52 slidably mounted in the bearing opening 53 provided 20 in the carrier in line with the axis of the shaft 12.

25 Sleeved over the shank 52 is a spring 54 having one end bearing against the head 50 and its opposite end against the bottom of the socket 34 to normally urge the head against the arms of the bell cranks for retaining the weights in retractive position when the engine is operating at normal speeds. The tension of the spring is, however, such as to allow the weights to move the pin outwardly in the direction of the cap portion 30 23 of the housing whenever the engine speed is such as to cause the centrifugal force of the weights to overbalance the spring. It is thus apparent that when the engine begins to race or exceed its rated R. P. M. the weights will cause 35 projection of the trip pin from the end of the governor carrier to trip a switch mechanism now to be described.

40 The switch mechanism is carried by the cap section of the housing and includes a fixed contact member 56 comprising a headed pin 57 having its shank 58 extended through an opening 59 in the cap at a point spaced laterally from the extended axis of the governor carrier. The shank 58 is threaded to receive a nut 60 to draw the contact head against its seat 61 in the housing and to provide a terminal 62 for securing the ground wire 63 of the magneto which leads 45 through a switch 64 in the cock-pit of the airplane for manually disrupting the ignition circuit by grounding the current generated by the magneto when it is desired to stop operation of the engine.

45 The switch mechanism also includes a contact plunger 65 having free sliding fit in a bearing opening 66 that is formed in the housing in line with the trip pin 51 and includes a cylindrical sleeve portion 67 having a through bore 68 to slidably mount a control pin 69 and to house a spring 70.

50 The control pin 69 is backed by the spring 70 which has its opposite end engaging the end 71 of an adjusting screw 72. The adjusting screw is threadedly mounted in the end of the bore farthest from the pin 51 and carries a lock nut 65 73 to engage the end of the contact plunger for locking the screw in adjusted position, as later described.

55 The outer end of the pin is retained by the spring 70 against an arm 74 of a bell crank latch lever 75 that is pivotally mounted on a pin 76 extending transversely of the housing below the plunger at a point between the governor carrier and the contact plunger, as shown in Fig. 2. The other arm 77 of the bell crank lever terminates in a hook 78 to engage a latch head 79

on the plunger, the latch head being cone-shaped to provide an inclined surface 80 to guide the hook into latching engagement with an annular shoulder 81 formed by the head. Also provided on the plunger is an annularly extending contact plate 82 arranged to engage the fixed contact member 56 but which is normally retained out of engagement therewith by the latch lever. 5

It is, therefore, obvious that the hook on the latch lever is engaged with the shoulder 81, the arm 74 thereof being engaged by the control pin and the spring 70 is retained thereby under tension to keep the latch engaged for holding the contact plate out of contact with the fixed contact member 56.

15 In order to set the latch I provide a lever 83 pivotally mounted in a slot 84 in the casing on a pin 85 and which has one end 86 projecting in the path of the contact plate and its opposite end 87 secured to a flexible cable 88 leading to 20 the cock-pit of the airplane.

25 In using the device constructed and assembled as described, the spring 70 is adjusted to the proper tension by manipulating the adjusting screw 72 to resist action of the trip pin 51 until the R. P. M. of the engine approaches the danger point. The contact plunger 65 is then moved into latching engagement with the latch lever 75 by pulling on the cable 88. This causes the end 86 of the lever 83 to engage the contact plate 30 82 for moving the plunger 65 until the hook 78 rides over the head 79 and engages the shoulder 81. The latch then retains the switch mechanism in set condition ready to be tripped by the trip pin 51 should the engine exceed a predetermined speed as set by the adjusting screw 72. 35

Under ordinary engine speeds, the pressure of the main spring 54 is enough to keep the trip pin from contact with the latch lever and the governor weights in retracted position. It is 40 thus apparent that under ordinary engine speeds, there are no moving parts subject to wear or to get out of adjustment but should the R. P. M. of the engine approach the danger point, the centrifugal force caused by the increased rotational speed of the shaft 12 will cause the governor weights to move outwardly. This causes the governor arms to move the trip pin 51 against tension of the spring 54 until the end thereof engages the arm 74 of the latch lever. When the 45 centrifugal force increases to overcome the resistance of the spring 70 the latch lever is rocked to cause release of the latch hook 78, whereupon the spring 70 expands and acts against the end of the adjusting screw to move the plunger outwardly in its bearing and the contact plate 82 50 into engagement with the fixed contact 56. This grounds the magneto current through the plunger 65 and housing 21 to stop operation of the engine in the same way as the manually operated 55 switch 64.

55 The pilot may re-establish the ignition circuit by pulling upon the cable 88 but if the cause of the excessive engine speed has not been repaired, the safety device will again function to stop 60 operation of the engine.

65 In case of a battery ignition system, the battery circuit will be closed through the contact plate 82 normally engaging a contact 89 supported by 70 the housing so as to engage on the inner face of the plate when the plunger is in latched condition, as shown in Fig. 5. In this construction, it is obvious that the ignition circuit will be broken when the safety device functions; otherwise the 75

construction will be identical to that shown in Figs. 1 to 4.

While I have particularly described the safety device as being mounted on the magneto, it is obvious that it may be mounted upon any convenient rotating shaft of the engine without departing from the spirit of the invention.

What I claim and desire to secure by Letters Patent is:

1. An ignition omitting mechanism for internal combustion engines including a housing, a fixed contact carried by the housing and adapted to be connected with an ignition circuit of an engine, a contact member movable in the housing to and from contacting relation with the fixed contact, a bell crank latch lever pivotally mounted in the housing and selectively engaging the contact member, trip mechanism in the housing engageable with an arm of said bell crank lever, a spring normally retaining said bell crank latch lever in latching engagement with the contact member and for urging said contact member into one position relatively to the fixed contact, and means responsive to speed of the engine for actuating the trip mechanism.

2. An ignition omitting mechanism for internal combustion engines including a housing, a fixed contact carried by the housing and adapted to be connected with an ignition circuit of an engine, a contact plunger slidably mounted in the housing and movable to and from contacting relation with the fixed contact, a control pin slidable in the contact plunger, a bell crank lever pivoted in the housing and having a latch-shaped head engageable with the contact plunger and having an arm engaged by said control pin, a spring normally urging the control pin into engagement with said bell crank arm to maintain said latching engagement with the contact plunger and to yieldingly urge said contact plunger into one position relatively to the fixed contact upon release of said latching engagement, trip mechanism in the housing for releasing the bell crank lever, means responsive to speed for actuating the trip mechanism, and means carried by the housing for relatching the bell crank lever with said contact plunger.

3. An ignition omitting mechanism for internal combustion engines including a housing, a fixed contact carried by the housing and adapted to be connected with an ignition circuit of an engine, a contact plunger slidably mounted in the housing and movable to and from contacting relation with the fixed contact to control the effectiveness of the ignition circuit, a control pin slidable in the contact plunger, a spring in the plunger engaging the control pin, means threaded in the contact plunger for tensioning the spring, a latch lever adapted to engage the contact plunger and

having an arm engaging the control pin to tension said spring, means for pivotally mounting the latch lever in the housing, a trip mechanism in the housing adapted to engage the latch lever to release the contact plunger, and a governor adapted to be actuated by speed of the engine for operating said trip mechanism.

4. An ignition omitting mechanism for internal combustion engines including a housing, a fixed contact carried by the housing and adapted to be connected with an ignition circuit of an engine, a contact plunger slidably mounted in the housing and movable to and from contacting relation with the fixed contact to control the effectiveness of the ignition circuit, a control pin slidable in the contact plunger, a spring in the plunger engaging the control pin, means threaded in the contact plunger for tensioning the spring, a latch lever adapted to engage the contact plunger and having an arm engaging the control pin to tension said spring, means for pivotally mounting the latch lever in the housing, a carrier member rotatably mounted within the housing, governor weights pivotally mounted on the carrier member, means adapted to be actuated by the engine for rotating the carrier member, and a spring tensioned trip member slidable in the carrier member for normally retaining the governor weights in retracted position but movable in response to movement of the governor weights to trip said latch lever to release the contact plunger.

5. An ignition omitting mechanism for internal combustion engines including a housing, a fixed contact carried by the housing and adapted to be connected with an ignition circuit of an engine, a contact plunger slidably mounted in the housing and movable to and from contacting relation with the fixed contact to control the effectiveness of the ignition circuit, a control pin slidable in the contact plunger, a spring in the plunger engaging the control pin, means threaded in the contact plunger for tensioning the spring, a latch lever adapted to engage the contact plunger and having an arm engaging the control pin to tension said spring, means for pivotally mounting the latch lever in the housing, a carrier member rotatably mounted within the housing, governor weights pivotally mounted on the carrier member, means adapted to be actuated by the engine for rotating the carrier member, a spring tensioned trip member slidable in the carrier member for normally retaining the governor weights in retracted position but movable in response to movement of the governor weights to trip said latch lever to release the contact plunger, and manual means carried by the housing for resetting the latch lever.

LELAND L. SCOTT.
